UNITED STATES PATENT OFFICE.

FRANKLIN MOULTON, OF ASHLAND, MASSACHUSETTS, ASSIGNOR OF ONE-HALF OF HIS RIGHT TO CHARLES M. ADAMS, OF SAME PLACE.

HEEL-TRIMMER.

SPECIFICATION forming part of Letters Patent No. 233,108, dated October 12, 1880.

Application filed July 22, 1880. (No model.)

To all whom it may concern:

Be it known that I, FRANKLIN MOULTON, citizen of the United States, residing at Ashland, in the county of Middlesex and State of Massachusetts, have invented certain new and useful Improvements in Heel-Trimming Attachments; and I do hereby declare that the following is a full, clear, and exact description of the same, reference being had to the annexed drawings, making a part of this specification, and to the letters and figures of reference marked thereon.

This invention consists in a device for attachment to heel-trimmers for the purpose of trimming or evening the soles of boots and shoes next to the uppers.

In the drawings, Figure 1 represents a heel-trimmer with my sole-evening device applied thereto. Fig. 2 is a detail view of the heel-trimming-knife gage and the device for trimming or evening the sole. Fig. 3 is a vertical section, showing the heel and edge of the sole in the act of being trimmed. Fig. 4 shows, in detail, my improved sole-edge trimmer with gage-plate for regulating its extent of cut.

A represents one of the usual forms of heel-trimming devices, where one non-rotatable straight or concave knife is used. B is the knife for trimming the outer side of the heel.

C represents my improved device, which is attached, by means of a screw, a, passing through the slot e, to the frame of the heel-trimmer, in front of and inside of the heel-trimming knife, where it is held firmly by a nut, b, on the other side. This device, as shown in Fig. 4, has a shoulder or step, d, to adapt it to fit the under side of the frame, said shoulder terminating at its lower part, on one side, in a knife, D, whose office it is to cut away and take out the single shaving which hangs over the counter of the boot, which operation is performed at the same time that the heel is trimmed, as shown in Fig. 3, the movement forward of the heel-trimmer at the same time carrying forward the thereto-attached knife D, so that the two operations of trimming the heel and evening the sole-edge and removing therefrom the strip of leather protruding therefrom

are accomplished at one movement of the machine.

The shouldered or enlarged portion of the attachment is recessed at e for the reception of a gage-plate, E, which is firmly secured therein by a screw or other suitable means, f, for the purpose of regulating the extent of cut of the knife D.

S represents the cutting or shaving as it is being removed from the edge of the sole by the movement forward of the knife D.

Heretofore the practice has been to remove the strip hanging over the counter by hand, either before or after the heel is trimmed; but by the use of this sole-evening device this strip may be readily removed and the edge of the sole trimmed or evened at the same time and during the movement forward of the heel-trimmer, to which the device is attached, thereby saving fully one-third of the labor usually expended upon trimming the edge of the sole next the upper, while at the same time accomplishing this result in a more perfect and reliable manner than where the operation is performed by hand.

The device may readily be applied to heel-trimmers generally where rotatable knives or burr-wheels are not used, as no alteration of the machine is required to adapt it to receive the attachment, the form of which allows it to be readily secured to the framing or arm immediately forward of the heel-trimming knife, as heretofore explained.

Having thus described my invention, what I claim as new, and desire to secure by Letters Patent, is—

The sole-edge trimmer herein described, consisting of the shouldered and recessed plate C, knife D, and gage E, substantially as and for the purpose set forth.

In testimony that I claim the above I have hereunto subscribed my name in the presence of two witnesses.

FRANKLIN MOULTON.
